UNITED STATES PATENT OFFICE.

EDWARD L. MORRIS, OF BOSTON, MASSACHUSETTS, ASSIGNOR TO NORTH & JUDD
MANUFACTURING CO., OF NEW BRITAIN, CONNECTICUT, A CORPORATION.

DESIGN FOR A BUCKLE.

45,154.

Specification for Design.

Patented Jan. 13, 1914.

Application filed September 22, 1913. Serial No. 791,232. Term of patent 7 years.

To all whom it may concern:

Be it known that I, EDWARD L. MORRIS, a citizen of the United States, residing at Boston, in the county of Suffolk and State of Massachusetts, have invented a new, original, and ornamental Design for Buckles, of which the following is a specification, reference being had to the accompanying drawing, forming part thereof.

Figure 1 is a view in perspective of the

buckle, showing my new design. Fig. 2 is a central longitudinal section thereof.

I claim:

The ornamental design for a buckle, as shown.

EDWARD L. MORRIS.

Witnesses:

CLARENCE C. KEMP,
H. ORVILLE CHANDLER.
